UNITED STATES PATENT OFFICE.

ERNEST LUNGE, OF LONDON, ENGLAND, ASSIGNOR TO COURTAULDS LIMITED, OF LONDON, ENGLAND, A BRITISH COMPANY.

PUMP AND LIKE DEVICE FOR CONTROLLING THE RATE OF DELIVERY OF FLUIDS.

Application filed November 13, 1925, Serial No. 68,874, and in Great Britain November 20, 1924.

This invention is for improvements in or relating to pumps and like devices for controlling the rate of delivery of fluids, and has for its object to provide an improved 5 construction of the same whereby, amongst other advantages, an unvarying rate of continuous delivery can be obtained. This feature is of particular importance in the manufacture of artificial silk, in which one of 10 the operations consists of squirting a spinning solution, for example, viscose, from a spinning-nozzle in the form of a filament or filaments; in order to produce a satisfactorily uniform product, it is necessary that 15 the nozzle should be continuously supplied with the spinning solution at an unvarying pressure. Owing to the nature of the materials used, it is not practicable to obtain the desired uniform pressure by means of 20 large reservoirs or the like, and the present invention provides an apparatus which can deliver the solution to the spinning-nozzles at an unvarying rate or pressure. It will be understood that this invention is not limited 25 to this particular application of it, but may be used with any liquid or fluid of which it is desired to obtain a continuous and uniform rate of delivery.

This invention comprises an apparatus for 30 obtaining a continuous delivery of liquid at constant velocity and constant pressure, the combination with two cyclically-actuated pumps whereof each has a delivery-stroke, which includes a period of delivery at the 35 desired uniform rate, towards an outlet common to both of them, and whereof the said uniform delivery periods successively overlap one another, of a chamber which is expanded at such a rate as to accommodate 40 within the apparatus during the overlapping periods and without altering the fluid pressure in the apparatus, all the flow towards the outlet that is in excess of the desired amount.

45 According to another feature of this invention, apparatus as above set forth is so constructed that the said chamber varies in volume at all times at the same rate as, but in the opposite sense to, the varying volume of one of the delivery pumps. Con-

veniently, the apparatus comprises two reciprocating delivery-pumps, and a third reciprocating pump which provides the chamber aforesaid to accommodate the excess flow.

55 According to another feature of this invention, the reciprocating pump which accommodates the excess flow is constituted by the rear face of the piston of one of the delivery-pumps, and that portion of the co-operating cylinder which is terminated by the said face.

According to yet another feature of this invention, apparatus as above set forth is characterized in that the excess flow of the 65 liquid which is being delivered towards the outlet is diverted into the accommodating chamber out of the path of flow towards the outlet, and thereby is temporarily subtracted from the total flow. When such apparatus comprises two delivery-pumps and a third or accommodation pump, as above mentioned, it is further characterized in that all three pumps can be put in direct communication with the main outlet.

75 Pumping devices in accordance with this invention may take various forms, and the invention also comprises certain details of construction and arrangement of pumps as hereinafter described with reference to the 80 accompanying drawings, in which—

Figure 1 is a plan of one construction in section on the line 1—1 of Figure 2;

Figure 2 is a cross-sectional view of the same on the line 2—2 of Figure 1, or Figure 4;

Figure 3 is an elevation in section on the line 3—3 of Figure 2;

Figure 4 is a plan;

Figure 5 is an end view in section on the line 5—5 of Figure 4;

Figure 6 is a detail;

Figure 7 is an elevation in cross-section of a second, modified construction;

Figure 8 is an elevation in section on the line 8—8 of Figure 9, of a third construction;

line 10—10 of Figure 11, of a fourth construction;

Figure 11 is a plan of the same construction;

5 Figure 12 is a sectional plan on the line 12—12 of Figure 13 of a fifth construction;

Figure 13 is a section on the line 13—13 of Figure 12;

10 Figure 14 is a sectional plan on the line 14—14 of Figure 15 showing a sixth construction;

Figure 15 is a section on the line 15—15 of Figure 14;

15 Figure 16 is a diagrammatic drawing showing the arrangement of a group of pumps; and

Figure 17 is a sectional elevation showing one form of operating means for reciprocating the pump plungers.

20 Like reference characters indicate like parts throughout the drawings.

Referring first to the construction illustrated in Figures 1—6, the construction and operation will be described in its broader 25 aspects first, and then the detail features will be considered.

30 The apparatus comprises essentially a supply-pipe 10 which communicates by means of a passage 11 with three cylinders 12, 13, 14, these cylinders communicating at their ends by means of a passage 15 which is a continuation of the passage 11. A valve 16, having a through passage 17, controls the passage 11 between the supply-pipe 10 and the cylinder 12, and a similar valve 18 with a through passage 19 controls communication between the cylinder 13 and the cylinder 14. The cylinder 14 is provided with an outlet passage 20 which, in the case 40 of artificial silk spinning-apparatus, communicates with a spinning-nozzle.

45 Each of the cylinders aforesaid is provided with a piston 21, 22, 23, respectively, and these pistons project from the open ends of the cylinders remote from the connecting passages 11, 15. The piston 23 is so operated that on its inward- or delivery-stroke, it has a perfectly uniform rate of movement except at the ends of its stroke 50 when its motion is being reversed; its return-stroke is made to take place in a lesser time and any convenient rate is used. The piston 22 is moved at exactly the same rate as the piston 23 but in the opposite sense, 55 that is to say, the piston 22 has an outward stroke which is perfectly uniform except at the ends, and a quicker return-stroke. The piston 21 has a cycle of movement similar to that of the piston 23, but its cycle is displaced in phase so that the period of uniform delivery during the inward movement of the piston 21 commences shortly before the corresponding period of the piston 23 stops, and continues until the piston 23 has completed 60 its return-stroke and has started its

next period of uniform delivery. The piston 21 then has a return-stroke which is completed before the piston 23 completes its delivery-stroke. The result is that the periods of uniform movement of the pistons 21, 23 70 successively overlap one another.

The valves 16, 18 are adjusted to open and close communication through the passages 11, 15 during the cycle of operations as hereinafter described.

75 In order to describe the operation of this device, let it be assumed that the cylinder 14 is filled with liquid, and that the piston 23 has started to move inwards at a uniform rate. The piston 22 is near the inner end 80 of the cylinder 13 and is moving outwards at the same rate; the piston 21 has just commenced its outward stroke. The valve 18 is in its closed position and the valve 16 is open. The movements of the various 85 pistons continue from this point in the manner above described. The liquid in the cylinder 14 is delivered through the outlet 20 at a perfectly uniform rate determined by the rate of movement of the piston 23. 90 The cylinder 12 is filled, as the piston 21 moves outward, by liquid flowing in from the supply-pipe 10 through the passage 11 and the valve 16. Also, the cylinder 13 is 95 filled by liquid entering in the same manner, as the piston 22 moves outward at its slow uniform rate.

100 Whilst the slow outward movement of the piston 22 is continuing, the piston 21 reaches the outward limit of its stroke, reverses, and commences its slow uniform movement inwards, and this rate of movement is equal to that of the piston 22 outwards. The piston 21, therefore, delivers liquid from the cylinder 12 at a rate equal to the rate at 105 which liquid flows into the cylinder 13. At this point in the cycle, the valve 16 can be closed, and the movements of the pistons 21, 22 can continue, since the volume between the faces of the two pistons remains 110 unchanged. Immediately thereafter, the valve 18, which has been closed, can be opened, without distributing the uniform delivery 115 of the cylinder 14 to the outlet, because the delivery which is taking place from the cylinder 12 is all accommodated within the cylinder 13.

120 It will be recollect that the piston 22 moves at exactly the same rate as the piston 23 but in the opposite sense. If, therefore, the piston 23 slows down so that its rate of delivery falls off from the desired uniform rate of delivery, the piston 22 will slow down by an equal amount. The piston 21, 125 however, continues its rate of uniform delivery, and the whole of this uniform rate can no longer be accommodated in the cylinder 13. The excess rate of delivery from the cylinder 12 is equal to the reduction 130 in the rate of accommodation provided in

the cylinder 13, and this reduction equals the reduction in the rate of delivery from the cylinder 14. But the liquid being delivered from the cylinder 12 can pass 5 through the passage 19 in the valve 18 into the cylinder 14 and directly to the outlet 20, so that the delivery from the cylinder 12 exactly compensates for the falling-off in the delivery from the cylinder 14. The piston 23 can now be stopped. The piston 22 10 stops at the same time, and the whole of the delivery from the cylinder 12 by the piston 21 passes to the outlet, and the desired uniform rate of delivery is therefore maintained. During the continuance of the uniform delivery of the piston 21, the piston 23 moves quickly outwards; the piston 22 similarly moves quickly inwards and, in so doing, delivers the liquid in the cylinder 13 15 into the cylinder 14 to fill it, the flow taking place through the passage 19 of the valve 18. When the cylinder 14 has again been filled the piston 23 reverses its movement and commences its uniform delivery-stroke. The piston 21 is now nearing the end of its 20 delivery-stroke, and the piston 22 is at the inner end of the cylinder 13 and commences its uniform outward stroke. The two cylinders 12, 14 are therefore both delivering towards the outlet at the desired uniform rate, 25 but the cylinder 13 is providing accommodation at the same desired rate for liquid from one of them. During this overlapping phase, the valve 18 can be closed so that the whole of the delivery to the outlet 20 is made by the piston 23. Immediately thereafter, the valve 16 can be opened so as to put the cylinders 12, 13 into communication with the supply-pipe 10, and immediately thereafter, the piston 21 can stop its uniform delivery and commence its return-stroke. This is the state which was assumed above at the commencement of the description of the cycle of operations and this cycle can be repeated indefinitely.

It will be seen that the piston 23 and the cylinder 14 constitute one delivery-pump, the piston 21 and the cylinder 12 constitute the other delivery-pump, and the piston 22 with the cylinder 13 constitute the accommodation chamber or pump referred to in the earlier part of this specification.

The detailed construction of this pump will now be described. The body of the device is formed as a casting 24 of suitable shape, and the cylinders 12, 13, 14 are formed as open-ended bores of uniform diameter therein. The connecting passage 11, 15 is formed as a through-bore (see Figure 2) and the ends are plugged at 25, 26. These plugs may be permanent, but it is preferred to make them removable so that the whole of the interior of the pump can be easily cleaned. The supply-pipe 10 is also formed 60 in the body of the pump, being a straight

bore through it from end to end, as shown most clearly in Figure 1, and there may also be provided a return-flow-pipe 27, (see Figure 2), whereby the circulation of the liquid may be maintained through all the pumping devices for ensuring its homogeneity, and also a pump may be rendered inoperative by causing it to deliver into the return-flow-pipe when necessary, such an arrangement being illustrated hereafter. The transverse connecting passage 11, 15 is preferably so situated that it provides communication from the bottom of the supply-pipe 10 to the bottoms of the cylinders 12, 13, 14, as shown in Figure 2, and an auxiliary 80 passage 28 is also used to provide communication between the tops of the cylinders 12, 13, 14. This arrangement ensures that when the pump is being filled with liquid in the first instance, the liquid flows into the bottom of each of the cylinders and rising therein expels the air through the upper passage 28 to the outlet 20, so that there is no possibility of any air being entrapped in the device. The valve 18 is of course formed with two passages 19 and 29 so as to open and close the passages 15 and 28 simultaneously so that they constitute in effect a single passage.

The body 24 is mounted on a base-plate 95 30 which is secured on any convenient bench 31. The pump-body is provided with a recess 32 (see left-hand side of Figure 2) to engage a lug 33 on the base 30, and the latter is furthermore provided with an up-standing flange 34, on the right-hand side in Figure 2, which has an overhanging lip 35 to engage the upper face of the body 24. The device is mounted on the base 30 by sliding it on sideways, from the left in Figure 2, and it is secured by means of a bolt 36 having an eccentric head 37 (see Figures 3 and 4) which engages in a recess 38 in the base 30. The bolt 36 extends through the body of the pump so that when it is 100 rotated to bring the head 37 into engagement with one of the walls of the recess 38, the pump-body is forced towards the right in Figures 3 and 4, closely against a similar neighbouring pump-body. The contact between two neighbouring pump-bodies takes place on the ends of that portion of the body in which the supply-pipe 10 is formed, so that when a number of bodies are assembled together in a row, the channels 10 constitute a supply-pipe extending throughout the length of the row. Any suitable packing may be interposed, in order to ensure that the various sections of the supply-pipe 10 may make a tight joint with one another. The packing may be and preferably is of an elastic nature in order that a reasonable tolerance may be allowed in the manufacture of the parts. By thus wedging the various units one against the other, and since 110 115 120 125 130

each is held from lifting off the base 30 by its engagement with the lugs 33 and lip 35 aforesaid, the pump-bodies are rigidly secured in place.

5 The driving of the various pistons is effected by means of rods 39, 40, 41, which extend along slots in the base 30. Where a plurality of the pumps are used in a group end-to-end, these rods extend throughout the 10 length of the group. Each rod actuates all the corresponding pistons of the group, and for each piston there is provided a peg 42 (see Figure 3) upstanding on the corresponding rod, so that it can engage the end 15 of the piston and push it on its inward stroke. The various pistons are pushed outwards by the pressure of the liquid in the supply-pipe entering the cylinders, or, in the case of the cylinder 14, by the pressure of 20 the liquid transferred to it from the other cylinder 13 and it will be appreciated that such outward movement of the pistons is controlled by the movement of the rods 39, 40, 41 so that the pistons are controlled 25 throughout the whole of the motion of the cycle of operations.

The valves 16 and 18 may be operated in any convenient manner. As illustrated in Figures 2, 3, 4 and 5, each valve projects 30 upwardly beyond the upper surface of the body 24 of the pump, and the two are rotatably coupled together by a link 43 pivoted on projections 44, 45 on the heads of the valves. The valve 16 is provided with 35 a second crank-pin 46, and a link 47 engaged therewith is coupled to a pin 48 upstanding on a rod 49 (see Figures 3 and 4) which is reciprocated to actuate the valves. With this arrangement it will be seen that 40 the two valves are operated simultaneously instead of in succession, as described above in the operation of the device. The only point to be noted with regard to the design 45 of the valves when they are operated simultaneously in this manner, is that the ports through them should be so proportioned as not to provide at any time a simultaneous 50 opening through both valves from all three cylinders to the supply-pipe. If it is desired to operate the valves successively in the manner first above described, this could be done by means of any simple lost-motion device, or by separate, but correctly timed, operating means.

55 The movements of the rods 39, 40, 41 and 49 may be imparted to them by any suitable or desired mechanism. The slow uniform delivery stroke can be made with a high degree of accuracy by providing a screw-feed, 60 as a uniform rate of rotation of a screwed-spindle can be obtained within very close limits, and a screw-thread can be cut to a very high degree of accuracy.

65 My co-pending application 68873 filed November 12, 1925 discloses mechanism for

reciprocating the pump rods. One such mechanism is shown in Figure 17 of the accompanying drawings in which the ends of three push-rods for the pumps are shown at 148. Three cams at 145 mounted for rotation as at 147 engage the rods 148 to operate the latter at the desired rate of speed.

70 The link 47 aforesaid is preferably made of a laterally yielding nature, so that it can be disengaged from the pin 48 (Figure 75 3) by lifting it up therefrom. This enables any individual pump or a group to be rendered inoperative without affecting the other pumps of the group, for the valves of 80 that particular pump would remain stationary. If the valves are left stationary in such a position that the valve 16 is left closed, the operation of the pump would continue until each of the pistons had been pushed to the innermost end of its stroke. 85 They would not move outwards again, because there would be no supply-pressure to effect this movement.

90 When filling and starting the pumps, the formation of air-pockets or bubbles within the device is prevented if the pistons are all retained at the innermost ends of their respective strokes, and this may be effected by means of the device illustrated in Figure 95 6. It consists of a plate 490 which is notched at 50 to fit over grooves 51 on the ends of the pistons (see Figure 4), and it is also notched as at 52 to engage with bolts 53 on the end face of the body 24 of the pump. The pistons are all pushed home 100 and the plate 490 dropped on the bolts 53 to engage with the three pistons and hold them against longitudinal movement. The valve 16 is turned into its open position so that the liquid can flow in from the supply-pipe to fill the various cylinders, or even 105 the normal operation of the pumps can be started without disconnecting the valves, as after one complete cycle the liquid will have 110 filled the device and normal delivery will follow thereafter.

115 Figure 7 illustrates a modified construction of pump. In this case, the supply-pipe is indicated at 53, and the three cylinders corresponding to 12, 13 and 14 of the construction above described are arranged as 120 at 54, 55 and 56. A single valve-member 57 controls communication between the supply-pipe and the first cylinder, and also between the second cylinder and the third 125 cylinder. The connecting passages are preferably arranged in pairs, as shown at 58, 59, and the final delivery takes place from the cylinder 56 through a passage 60. This passage 60 opens into a chamber 61 125 provided with a rotatable valve-member 62. In one position of this valve-member, the passage 60 is open to the normal outlet 63, and if this valve-member is rotated through 180° the passage 60 is placed in communica- 130

tion with a return-flow pipe 64 corresponding to the pipe 27 of Figure 2. This bypass device is used when it is desired to stop the delivery of one of a series of pumps for any reason. A similar by-passing device may be provided on the pump illustrated in Figures 1-5, if so desired.

The construction illustrated in Figure 7 may be operated by means similar to that illustrated in Figures 1-5, in so far as the pistons for the various cylinders are concerned, and the valve 57 can be operated as were the two valves 16, 18, when coupled together.

In Figures 8 and 9, yet another construction is illustrated. In this case, the supply-pipe is indicated at 65 and the three cylinders, corresponding to 12, 13 and 14 aforesaid, are arranged in a vertical plane above the pipe 65, at 66, 67, 68. The outlet 69 from the cylinder 68 can be put into communication with the main outlet 70, or with a return-flow-pipe 71 by means of a bypass valve 72. A feature of this construction is that the various pump-cylinders are constituted by annular chambers formed by two piston-members of differing diameter. The controlling valves are indicated at 73, 74 respectively. The first pump-chamber 66 is constituted by the annular space surrounding a plunger 75 which is of smaller diameter than a plunger 76 which engages it endwise. Movement of the two plungers towards the right in Figure 9 constitutes the rapid inlet or suction stroke of this pump, and the slow uniform delivery-stroke takes place in the opposite direction. The other two pumps are constructed similarly, but they are arranged to extend in opposite directions from the connecting passage 77, that is to say, the accommodation pump has its larger plunger 78 on the left, and its smaller plunger 79 on the right, whilst the delivery-pump has its larger plunger on the right at 80 and its smaller plunger on the left at 81. The operation of this pump is exactly the same as the operation of that described in connection with Figures 1-5, and the two pumps 78, 79 and 80, 81 have exactly the same movement but they are in opposite phase. That is to say, when the plunger 80 moves towards the left on its delivery-stroke, the plunger 78 has to move on its suction-stroke. With the above-described arrangement of the parts, this movement is also towards the left in Figure 9, so that the four plungers 78, 79, 80, 81 all move to-and-fro in exactly the same manner.

It will be seen that by adopting this arrangement of annular pump-chambers, the parts corresponding to the pistons of the pumps extend endwise right through the pump-body, and when a number of pumps

are assembled together side-by-side in close proximity, the corresponding plungers can abut one another if their lengths are suitably selected. A drive can then be imparted to the whole of the pumps of a group by driving the plungers of the end unit. Such an arrangement is illustrated diagrammatically in Figure 16, in which a series of pump-bodies are indicated diagrammatically at 140 with their corresponding plungers aligned with and abutting one another 75 as shown at 141, 142. The supply- and return-flow-pipes whereby circulation of the liquid can be maintained are conveniently formed as through-bores 143, 144 respectively, which open into one another at the ends 80 of the pump body. Very great simplicity is thereby attained, since any number of units can be assembled end-to-end and a single driving device provided only at one end of the group. The return-stroke may be effected by means of any suitable driving mechanism, a yielding hydraulic device being particularly suitable in that it will hold the plungers up against the driving-member which thereby effectively controls their 85 movement in both directions.

In the construction illustrated in Figures 10 and 11, the three pump-chambers are indicated in the same sequence as in the descriptions of the previous constructions, at 82, 83, 84, the supply-pipe being shown at 85, and the return-flow-pipe at 86. A single valve-member 87 is used to control the communication between the supply-pipe and the cylinders, this valve being rotatable into 100 two positions. A chamber 88 in the valve is provided with downward and upward extensions 89, 90 respectively. In one setting of the valve, the cavity 89 provides communication from the supply-pipe 85 to the 105 first and second cylinders 82, 83, the third cylinder 84 being then open only to the outlet 91, whilst in the other setting of the valve, the supply-pipe 85 is shut off and the cylinders 82, 83 are in communication 110 through the cavity 90 with the cylinder 84 and the outlet. The operation of this device for controlling the rate of delivery of the fluid is exactly the same as with the construction illustrated in Figures 1-5, and 115 various other details of construction can be similar to any of the constructions already described. Thus, the pumps could be constituted by plungers working in open-ended bores, or by coaxial plungers of different 120 diameter, but such details need not be repeated.

The construction illustrated in Figures 12 and 13 is similar to the constructions previously described in its mode of operation, but it differs in that only two cylinders are used, and a piston in one of them constitutes by one of its faces the piston of

the delivery-pump, and by the other of its faces the piston of the accommodation pump.

Referring to these figures, the apparatus 5 comprises a body 92 provided with four borings extending through it, and with a supply-pipe 93. The bore 94 accommodates a sliding valve 95 which opens or closes a passage 96. This passage opens into a 10 cylindrical bore 97 which has a close-fitting plug 98 reciprocatable in it. This plug is moved by means of plungers 99, 100 which extend endwise from the end of the body to co-operate with corresponding plungers of 15 another similar device in the manner above described. The plunger 99 is of less diameter than the plug 98, so as to provide an annular pump-chamber around it. As illustrated, the plunger 100 is similarly made of 20 smaller diameter than the plug 98, but this is not essential, as the annular space around the plunger 100 is opened to atmosphere and is not used as a pumping-chamber. The plungers are a good fit in bushes such as 25 101 which are screwed or otherwise secured in the body of the casing, this construction being necessitated by the fact that the plug 98 is of larger diameter than the plunger 99.

The pumping-chamber 97 is open at all 30 times by a passage 102 to a valve-chamber 103, this chamber being provided with a valve 104 which can open or close communication therefrom to a passage 105. The chamber 103 also communicates at its other 35 end with a passage 106, but this passage is never closed. The passages 105, 106 communicate respectively with the two ends of a cylindrical bore 107 in which there slides a close-fitting plug 108 similar to the plug 98. The plug is actuated by plungers 109, 40 110 each of smaller diameter than the plug so that two annular chambers are provided, one at each end of the chamber 107. The plug 108 constitutes by its face 111 the piston of a delivery-pump, and by its other 45 face 112 the piston of the accommodation pump. The main outlet from the delivery-pump is indicated at 113, being opposite the passage 105 aforesaid which is controlled 50 by the valve 104.

The operation of this device in so far as it comprises two delivery-pumps and an accommodating pump, is similar to that of the construction illustrated in Figures 1-5. 55 With the parts in the position shown in Figure 12, the piston or plug 98 has started its uniform delivery, moving towards the left. The liquid is being delivered through the passage 102, chamber 103, passage 105 60 (which the valve 104 has opened) to the outlet 113. The plug or piston 108 is about to start its quick return movement towards the left, and in so doing the liquid in the accommodation chamber 107 is transferred 65 through the passage 106, chamber 103, pas-

sage 105, to the other side of the piston 108, and this charging of the delivery-pump on the right-hand side of the piston 108, is completed before the piston 98 completes its uniform delivery-stroke. The piston 108 then commences its stroke of uniform delivery rate towards the right, and thereby delivers liquid to the outlet 113, and the piston 98, which is nearing the end of its uniform delivery period, delivers its liquid into the accommodation space to the left of the piston 108. The valve 104 is then closed and the valve 95 is opened. The piston 98 then starts its quick return-stroke and draws in a fresh charge of liquid from the supply- 70 pipe through the passage 96 and liquid also flows during this period through the passage 102 and chamber 103 into the accommodation chamber on the left of the piston 108. The piston 98, having reached the end 75 of its stroke towards the right in Figure 12, reverses its motion and commences its rate of uniform delivery and the valves are then readjusted to the positions shown in Figure 12, and soon thereafter the piston 108 80 reaches the end of its delivery-stroke, that is to say, the parts have all returned to the positions illustrated and the cycle of operations 85 has been completed and is ready for starting a new cycle. 90

In the construction illustrated in Figures 14 and 15, the apparatus comprises a body 114 provided with a number of longitudinal borings through it. Of these the supply-pipe is constituted by the boring 115, 100 and the return-flow-pipe by 116. The three pump-chambers are shown at 117, 118 and 119 respectively, and there are also provided two other bores 120 and 121 to receive sliding cylindrical valves. Transverse 105 passages 122, 123 and 124 provide communication from the inlet-pipe to the various valve spaces and cylinders, and the outlet from the pump is indicated at 126, this outlet communicating alternatively with a spinning-nozzle on 127 or with the return-flow-pipe 116 by means of a suitable by-pass valve 128. 110

In this case all the pistons are of the differential type, as shown in Figure 14, but the 115 two parts are preferably separated and held apart by the internal pressure of the liquid which is being delivered, so as to avoid any interference with the free flow of the liquid and in particular to avoid any undesirable 120 effects of surface tension at the junction between the narrower and wider piston sections. As shown in Figure 14, the cylinder 117 has a larger piston 129 and a smaller piston 130. The corresponding parts of the 125 cylinder 118 are shown at 131, 132 respectively.

The pairs of pistons 129, 130 and 131, 132 are moved simultaneously in the same direction, that is to say, alternately towards the 130

right and towards the left in Figure 14, by means of a rod underneath the pump-body carrying a member 133 which engages each pair of pistons. The piston 134, which is in the cylinder first entered by the liquid from the supply-pipe 115, is moved in the manner above described oppositely to the piston 131 by a suitable push-rod 135. The two valves, of which one is shown at 136, in Figure 14, may be operated in any convenient manner, preferably by arranging that the valves of different units abut one another lengthwise and are all moved simultaneously by a suitable device at the end of the row.

15 The various passages are closed where necessary by plugs 137 which are shown as of tapering formation with a yielding packing 138; these plugs are held in place by a suitable bracket 139 on the bench against which the pump body is pressed. This form of plug is illustrated as a modification which can be applied to any of the constructions of pump hereinbefore described.

The operation of this particular construction need not be described in detail, as it is exactly similar to the various constructions hereinbefore described, it being understood that the liquid passes from the supply-pipe 115 through the valve-chamber 120 into the first pump-cylinder 119; the liquid is delivered from this chamber 119 either directly to the outlet by the passages 123, 124, or in another phase of the cycle is delivered into the chamber 118 and is delivered thence to the chamber 117, from which it is subsequently delivered to the outlet.

Any desired means, such as that shown in Figure 17, may be used for imparting the requisite movement to the pump plunger.

40 A number of different embodiments of this invention have been described, in order to show the great flexibility of design which is possible with devices in accordance with this invention. The operation of all of them is similar, in so far as the two pumps deliver the liquid successively to the outlet, and during the overlapping periods of their delivery, the liquid from one of the pumps is diverted from its normal path of flow from the pump towards the final outlet, into a chamber which expands at a rate exactly equal to the rate of delivery of liquid in excess of the desired rate. It will also be appreciated that in order to prevent any irregularities in the rate of delivery arising from the operation of the valves controlling the various passages, these valves should be of a type which in its opening and closing movements does not alter the cubic content 45 of the pump charge. Apart from this limitation, any desired construction or arrangement of valves may be used. Whilst a number of constructions have been described, it is to be understood that the invention is not limited to them, or to any other specific con-

struction, for it will be obvious that many other modifications and arrangements of device may be used in accordance with this invention for providing a continuous and uniform delivery of fluids.

What I claim as my invention and desire to secure by Letters Patent is:—

1. In apparatus for obtaining a continuous delivery of liquid at constant velocity and constant pressure, the combination of two reciprocating pumps, a delivery outlet common to both of them, means for operating said pumps so that each has a delivery-stroke, which includes a period of delivery at the desired uniform rate towards said outlet, and the said uniform delivery periods successively overlap one another, a chamber, means for varying the volume thereof at the same rate as, but in the opposite sense to, the varying volume of one of the delivery pumps, and means providing communication between said chamber and said pumps.

2. In pumping apparatus, the combination of two reciprocating delivery pumps, means for operating them so that each has a delivery stroke which includes a period of uniform delivery that overlaps at both ends the period of uniform delivery of the other, a third reciprocating pump which moves oppositely to one of said pumps, and means providing communication between each of said first pumps and said third pump.

3. In pumping apparatus, the combination of a double-ended reciprocating pump, a single-ended reciprocating pump, means for operating said pumps so that each has a delivery stroke which comprises a period of uniform delivery, which period overlaps the similar period of the other pump, and means providing communication from both of said pumps to an outlet common to both of them.

4. In pumping apparatus, the combination of two reciprocating pumps which deliver alternately without cessation to an outlet common to both of them, and a chamber of variable volume which accommodates all that portion of the total delivery in excess of a predetermined quantity.

5. In pumping apparatus, the combination of a pump-cylinder, a plunger therein, means for reciprocating said plunger in such manner that it moves with a uniform velocity during a portion of its delivery stroke, and pauses after each stroke, a second pump-cylinder, a plunger therein, means for reciprocating said plunger in such manner that it moves with a uniform velocity during a part of its stroke, and such part overlaps the similar part of the stroke of the first-mentioned plunger, and such that said second plunger pauses after each of its strokes, a chamber, means for varying the volume thereof in opposite phase to one of said pumps, a supply-pipe, a delivery-pipe, means providing communication between

said supply-pipe and each of said pumps and said chamber, valve-means controlling said communicating means, valve-operating means adjusting said valves during the 5 pauses aforesaid which occur between the working strokes of the pump, and means providing communication from each of said pump cylinders to said delivery-pipe.

6. In pumping apparatus, the combination 10 of two reciprocating pumps operated at such

a rate that they have successively overlapping periods of uniform delivery, a chamber which is supplied from one of said pumps, and delivers to the other of said pumps, and means for varying the volume of said 15 chamber in such manner that it accommodates at all times any flow of liquid in excess of the maximum delivery of one pump.

In testimony whereof I affix my signature.

ERNEST LUNGE.
